R. H. Hamilton

INVENTOR.

William H. Summers,
BY
Warren D. House
His ATTORNEY.

UNITED STATES PATENT OFFICE.

WILLIAM H. SUMMERS, OF FLORENCE, KANSAS.

APPARATUS FOR TREATING CRUDE OIL.

1,405,876.

Specification of Letters Patent.

Patented Feb. 7, 1922.

Application filed August 16, 1920. Serial No. 403,928.

To all whom it may concern:

Be it known that I, WILLIAM H. SUMMERS, a citizen of the United States, residing at Florence, in the county of Marion and State 5 of Kansas, have invented a certain new and useful Improvement in Apparatus for Treating Crude Oil, of which the following is a specification.

My invention relates to improvements in 10 apparatus for treating crude oil.

The object of my invention is to separate 15 from the oil the thicker and heavier ingredients in the oil, such as paraffin, thick heavy oil, magnesia, sand, dirt and other impurities.

A further object of my invention is to provide an apparatus which is simple in construction, cheap to make, and to apply to a tank in the field, which is durable and not 20 liable to get out of order, which has large capacity, which may be readily cleaned, and the screened material easily removed from the tank, and which is efficient in operation.

The novel features of my invention are 25 hereinafter fully described and claimed.

In the accompanying drawing, which illustrates the preferred embodiment of my invention,

Fig. 1 is a vertical sectional view of a settling tank provided with my improvement.

Fig. 2 is a top view of the same.

Similar reference characters designate similar parts in the different views.

1 designates an ordinary field settling tank 35 of relatively large capacity having an open top and an outlet or discharge pipe 2, adjacent to the upper end. The bottom of the tank is preferably inverted cone shape having a central discharge opening 3 adapted to 40 be closed by a shut-off valve 4. 5 designates a supply pipe connected with any suitable source of supply and having its lower end discharging into the tank adjacent to the bottom thereof, said pipe serving as the oil 45 inlet for the tank.

Extending transversely across the tank intermediate of the inlet 5 and the outlet 2, is a screen which is adapted to permit the passage therethrough of the lighter thinner part 50 of the oil, but which intercepts and prevents the passage therethrough of the heavier ingredients, such as thick heavy oil and paraffin and foreign substances, such as magnesia, sand or dirt.

55 The screening material is preferably canvas, which may be of a mesh best suited to

arrest the particular ingredients or substances which may be carried by oil from different wells.

The screen is composed, preferably, of a 60 plurality of sections, each section consisting of a frame 6, having canvas 7, extending across the opening in the frame and attached to the frame, each frame being removably supported upon suitable supporting devices, 65 such as angle irons 8, fastened to the inner wall of the tank 1. The frames 6 are arranged in zig-zag relationship to each other, with relationship to the horizontal plane, whereby a large area of screening surface is 70 afforded.

In the operation of my invention, the crude oil from a suitable source of supply, not shown, is discharged into the tank 1 through the pipe 5. The valve 4 is normally closed. 75 The thinner lighter oil passes through the canvas 7 and is discharged from the tank through the outlet pipe 2. The paraffin, thick heavy oil, sand and dirt and other thick heavy substances are arrested by the 80 canvas screening 7 and fall by gravity to the bottom of the tank, from which they can be removed from time to time by opening the valve 4.

When desired, the frames 6 can be independently removed for the purpose of being cleaned or for the renewal of worn-out screening material, after which the frames may be replaced in their operative positions.

I do not limit my invention to the structure shown and described, as many modifications, within the scope of the appended claims, may be made without departing from the spirit of my invention.

What I claim is:—

1. In an apparatus for treating crude oil, a settling tank having an inlet for oil and an outlet for oil above said inlet, supports attached to the inner wall of the tank and arranged in zig-zag relation to each other, and a screen extending transversely entirely across the tank intermediate of the inlet and the outlet and comprising sections, each being independently removable, the sections being disposed in zig-zag relation to each other and supported at their ends respectively by said supports, substantially as set forth.

2. In an apparatus for treating crude oil, a settling tank having an inlet for oil and an outlet for oil above said inlet, zig-zag supporting means attached to the inner wall

of said tank, and removable screen sections, each comprising frames across which screening material is attached, each of said screen sections being independently removably mounted on said zig-zag supporting means and being in zig-zag relation to each other and extending as a whole entirely across the tank, substantially as set forth.

3. In an apparatus for treating crude oil,
10 a settling tank open at the top and having an inlet for oil and an outlet for oil above

said inlet, screen supporting means on the inner wall of said tank, and a removable screen extending transversely entirely across said tank and comprising sections arranged in zig-zag relation to each other and resting upon and arranged each to be independently lifted from said supporting means, substantially as set forth. 15

In testimony whereof I have signed my name to this specification.

WILLIAM H. SUMMERS.
